**COMBINED RECHARGEABLE DISPENSING
CONTAINER AND OVERCAP THEREFOR**

William Horvath, Chatham, N.J., assignor to
Thiokol Corporation, Bristol, Pa.

Filed Apr. 27, 1973, Ser. No. 355,249

Term of patent 14 years

Int. Cl. D9—01

U.S. Cl. D9—8

Fig. 3

Fig. 4

Fig. 2

Fig. 1

FIG. 1 is a side perspective view of a combined rechargeable dispensing container and overcap therefor showing my new design;

FIG. 2 is a front perspective view with the overcap removed;

FIG. 3 is a top perspective view with the overcap in place; and,

FIG. 4 is a front elevational view of the bottom portion of the container showing the side walls thereof.

I claim:

The ornamental design for a combined rechargeable dispensing container and overcap therefor, as shown.
